UNITED STATES PATENT OFFICE.

LUIGI ANGIULLI, OF NEW YORK, N. Y.

DESIGN FOR AN AUTOMOBILE-HORN.

40,251.

Specification for Design.

Patented Sept. 7, 1909.

Application filed July 2, 1909. Serial No. 505,759. Term of patent 3½ years.

To all whom it may concern:

Be it known that I, LUIGI ANGIULLI, a subject of the King of Italy, residing at New York city, in the county and State of New York, have invented a new, original, and ornamental Design for Automobile-Horns, of which the following is a specification, reference being had to the accompanying drawings, forming part thereof.

The figure is a perspective view of an automobile horn, showing my new design.

I claim:

The ornamental design for an automobile horn, as shown.

LUIGI ANGIULLI.
